PIPE TONG

Richard K. Hertel, Vernon, Calif., assignor to
 Byron Jackson Co., Huntington Park, Calif., a
 corporation of Delaware

Application November 25, 1935, Serial No. 51,442

3 Claims. (Cl. 81—66)

This invention relates to pipe tongs, and, more especially, to improvements in hand tongs for use on oil well tubing, such as tongs shown in Patent No. 1,764,124 granted June 17, 1930, to Nelson K. Smith. Such tongs are characterized by a pair of pivoted jaw members adapted to completely encircle the pipe, and a lever pivoted to one of the jaws and having a lug on the pivot end thereof adapted to engage the free end of the other jaw to force the jaws into pipe engaging position.

An object of the present invention is to provide a tong having the foregoing characteristics, while improving the design to provide greater strength.

Another object is to provide improved means for holding the jaws in the open or closed positions.

Another object is to provide means for locking the tong on the pipe so that it can be used as a back-up tong without removal from the pipe.

Other objects and advantages will be apparent from the following descriptions and drawing:

Fig. 1 is a plan view of a pipe tong constructed in accordance with the provisions of this invention, a portion of the handle being broken away to contract the view.

Fig. 2 is a back elevation of Fig. 1 showing the locking device.

Fig. 3 is a horizontal view, mainly in section, viewed from the line indicated by 3—3 on Fig. 2.

There is provided a hook-shaped body 6 provided with a curved inner face 12 adapted to bear against the surface of the pipe P on one side. The pipe is gripped on the opposite side by a swinging latch gate or jaw 13 provided with a curved inner face 14.

The inner face 14 is provided near the free end of the latch with a die 15 which is brought into engagement with the pipe when the latch jaw is in the closed position shown in Fig. 1. The die 15 is removably retained in a die slot 44 by any suitable means such as the cotter keys 47, which extend through a hole 46 in lugs 45 formed on the latch jaw 13.

The latch jaw 13 is pivoted by a bolt 16 to the body 6 and the body and latch jaw together constitute a pair of pivotally connected jaws between which the pipe is clamped. The pivot 16 passes through a hole 17 in the body 6. The pivoted end of the latch jaw 13 is slotted to provide upper and lower flanges 8, 9 adapted to receive the end of the body 6. The flanges 8, 9 are provided with holes 18 to receive the pivot bolt 16.

The free end of latch jaw 13 is provided with a handle comprising a bar 20 and an outwardly

projecting arm 21. The bar 20 is secured at its middle to the arm 21 and the opposite ends of the bar project upwardly and downwardly from the arm 20 so that some of the fingers of the operator can be placed on the upper portion of the bar and some on the lower portion.

Near its free end 44 (Fig. 3), the latch jaw 13 is provided in its outer face with a recess 22, one wall of which forms a shoulder 23 which is engaged by a shoulder 24 on an operating lever 10 or handle 25 which is pivoted at 26 to the body 6. The pivot of the lever 25, in this instance, is in the form of a bolt that passes through a hole 27 in lever 25. The lever end of the body 6 is slotted to form upper and lower flanges 5, 7 adapted to receive the end of the lever 25. The pivot bolt 26 passes through holes 28 formed in the flanges 5, 7.

The shoulder 24 is formed by one face of a projecting lug 29 formed on the end of lever 25. The lever 25 constitutes the handle of the tong and provides a lever adapted, when the handle is moved in the position shown in Fig. 1, to thrust the latch jaw 13 inwardly so as to clamp the pipe between the latch jaw 13 and the body 6.

The body 6 is provided near its middle portion with a chamber or pocket 4 adapted to receive a coil compression spring 33 enclosing a plunger 40. The spring 33 bears at one end against a seat 31 formed by the forward wall of the pocket 4 and at its other end bears against a shoulder 41 formed by a head 42 formed on the rear end of the plunger 40. The plunger 40 is curved to conform roughly to the curvature of the body 6. The forward end of the plunger 40 extends through an opening 31a formed in the forward wall 31 of pocket 4. The rear end, or head 42, of the plunger 40 extends through an opening 11a formed in the rear wall 11 of the pocket 4. The head 42 of plunger 40 is provided with a rounded nose 50 forming diverging cam faces 51, 52.

The pivot end of the tong lever 25 is provided with a lateral extension 38 having a rounded nose forming diverging cam faces 39a and 39b. The cam faces 39a and 39b are adapted to bear against the cam faces 51 and 52, respectively, of the plunger head 42 in body 6, so as to releasably hold the body and lever in the closed or open position as may be desired.

The latch jaw 13 is provided with a recess or pocket 3 (similar to pocket 4 in body 6) enclosing a coil compression spring 38 through which there extends a plunger 36 provided with a head 19 forming a shoulder 37 against which one end of the spring seats. The other end of the spring 55

bears against a seat formed by the wall 30 of the pocket. One end of the plunger 36 extends through a hole 10 formed in the wall 30. The plunger head 19 extends through a hole 35a in the wall 35 of the pocket 4. The head 19 is formed with a rounded nose providing diverging cam faces 34a and 34b.

The end of body 6 adjacent the pivot 16 is provided with an extension 32 having a rounded nose 10 forming diverging cam faces 32a and 32b. The cam faces 32a and 32b on the body 6 are adapted to bear against the cam faces 34a and 34b, respectively, of the plunger head 19, so as to releasably hold the body and latch jaw in the closed 15 or open position as may be desired.

The flanges 8, 9 on the pivot end of the latch jaw 13 extend over and conform to the inner curved portion of body 6 for a short distance, so that when the tong is in the open position shown 20 in Fig. 3 the flanges 8, 9 extend outwardly from the body 6. Thus when the tong is thrust against the pipe the flanges 8, 9 are first to contact the pipe and serve as levers to force the cams 19, 32 to cross over center, whereupon the spring 38 25 and its cam plunger 36 force the latch jaw to the closed position and hold it there.

When the latch jaw 13 has been moved to closed position, as described above, the shoulder 23 on the latch jaw is in position to be engaged by the 30 shoulder 24 on the tong lever 25. The lever is swung on its pivot 26 so that the cams 42, 38 cross over center whereupon the shoulders 23 and 24 can be engaged and the lever is held in the closed 35 position by the spring plunger 40 and its associated cam surfaces.

To remove the tong from the pipe, the lever is swung on its pivot from the position shown in Fig. 1 to the position shown in Fig. 3.

In order that the tong can be used as a back-up tong without removing it from the pipe, I provide a cam lock in the form of a lever 60 secured to the lever 25 near its pivot end by means of a pivot bolt 61 extending through holes in the levers 25 and 60. The tong lever 25 is provided with 40 a recess 62 adapted to receive the cam lever 60. The cam lever 60 is provided with a cam surface 63 adapted to bear against a cam surface 64 formed on an extension of wall 11 of the body member 6. The body 6 is slotted at its rearward 45 end forming flanges 5, 7 between which the tong lever 25 is received. A spring washer 67 is provided around the pivot bolt 61 and between the cam lever 60 and the tong lever 25. The spring washer is adjusted to hold the cam lever firmly 50 (but movable by hand) in any given position. In Fig. 1 the cam lock is shown in the locked position. It will be noted that with the lock in this 55 position the tong lever can not be swung on its pivot to the releasing position.

60 The spring-pressed cam plungers 36, 40 together with their associated cams provide a construction which enables the tong to grip the pipe tightly and yet the lever and jaw members are easily moved to and from the open and closed 65 positions.

66 The curvature of the plungers 36, 40 permits the plungers to be of relatively great length without requiring that the jaw members be any wider than is necessary for adequate strength. Because 70 of the great length of the plungers, the springs 33, 38 can be of considerable length. This construction results in a low spring stress without appreciable lateral distortion and yet gives a relatively long plunger travel.

The arrangement of the jaw sections such that the latch jaw is the female member, where it is pivoted to the body, is particularly desirable, since the latch jaw is necessarily the smaller member and, without this construction, would be 5 the weaker member and most liable to breakage.

I claim:

1. A pipe tong comprising pivotally connected jaws comprising a body member and a latch jaw member, a lever pivoted to one end of said body 10 and provided with a shoulder, the latch jaw provided with a shoulder engageable with the first mentioned shoulder when the latch jaw is in closed position and the lever is moved to closed position, the latch jaw and lever being movable into 15 open positions, pockets formed in said body and jaw members, spring-pressed plungers slidably received in said pockets, said plungers being provided with heads having noses forming diverging cam faces, an extension formed on the pivoted 20 end of said lever and provided with a nose forming diverging cam faces adapted to co-act with the diverging cam faces on the plunger in said body member and an extension formed on the other end of said body member, said extension 25 being provided with a nose forming diverging cam faces adapted to co-act with the diverging cam faces on the plunger in said latch jaw.

2. A pipe tong comprising a body member, a latch jaw member provided with spaced flanges 30 at one end, said body being received between said flanges and pivoted thereto at one end, said body being provided at its other end with spaced flanges, a tong lever adapted to be received between said body flanges and pivoted thereto, a 35 shoulder on the free end of the latch jaw, a shoulder on the pivoted end of the tong lever engageable with the shoulder on said latch lever when said latch jaw and tong lever are moved to closed position, a pocket formed in said body member, a 40 pocket formed in said latch jaw member, spring-pressed plungers slidably received in said pockets, said plungers being provided with noses forming diverging cam faces, an extension formed on the pivoted end of said tong lever, and provided with 45 a nose forming diverging cam faces adapted to co-act with the cam faces on the plunger in said body member, an extension formed on the other end of said body member and provided with a nose forming diverging cam faces adapted to co-act with the cam faces on the plunger in said 50 latch jaw member.

3. A pipe tong comprising a body member and a latch jaw member curved to conform to the pipe contour, said latch jaw being pivoted at one end to 55 said body, a tong lever pivoted to said body at the other end, a shoulder on the free end of the latch jaw, a shoulder on the pivoted end of the lever engageable with the shoulder on the latch jaw when said members are moved to the pipe gripping position, pockets formed in the body and latch jaw, spring-pressed plungers slidably received in said pockets, said plungers being curved to approximate the curvature of said body and jaw, a nose forming diverging cam faces provided 60 on one end of each plunger, a nose forming diverging cam faces provided on the pivoted end of said lever and adapted to co-act with the cam faces of the plunger in the body member, a nose forming diverging cam faces provided on the end 65 of said body adjacent said jaw, said cam faces being adapted to co-act with the cam faces on the plunger in the jaw member.

RICHARD K. HERTEL.
